TELEVISION ANTENNA FOR INDOOR USE

Marvin P. Middlemark, 99-05 63rd Drive,
Rego Park, N.Y. 10074

Filed Oct. 20, 1965, Ser. No. 87,617

Term of patent 14 years

(Cl. D26—14)

FIG. 1

FIG. 2

FIG. 3

FIGURE 1 is a front elevational view of a television antenna for indoor use showing my new design;

FIGURE 2 is a top plan view thereof; and

FIGURE 3 is a side elevational view thereof.

The dominant portions of my design reside in those portions shown in full lines.

I claim:

The ornamental design for a television antenna for indoor use, as shown and described.
